CHARLES L. COFFIN

ATTYS

UNITED STATES PATENT OFFICE.

CHARLES L. COFFIN, OF NACOOCHEE, GEORGIA, ASSIGNOR TO ELECTRIC METAL WORKING COMPANY, OF DETROIT, MICHIGAN, A CORPORATION OF MICHIGAN.

METALLIC BARREL.

No. 845,760.

Specification of Letters Patent.

Patented March 5, 1907.

Application filed April 2, 1906. Serial No. 309,561.

To all whom it may concern:

Be it known that I, CHARLES L. COFFIN, a citizen of the United States of America, residing at Nacoochee, in the county of White and State of Georgia, have invented certain new and useful Improvements in Metallic Barrels, of which the following is a specification, reference being had therein to the accompanying drawings.

The invention relates particularly to metallic packages or barrels of the insulated type wherein the body is composed of shell-sections spaced one from another to provide an insulating space or chamber; and it consists in the novel and peculiar construction of a barrel of this type and in various details of construction, as will be more fully hereinafter set forth and illustrated.

In the drawings, Figure 1 is a vertical central section through a metallic barrel embodying my invention. Fig. 2 is a similar view showing a modified construction. Figs. 3, 4, and 5 are modifications. Fig. 6 is a detached view of one of the drawn sections of which either of the shells may be composed, and Figs. 7, 8, and 9 are detached sectional views illustrating the means of uniting the drawn sections.

Referring to Fig. 1, A represents an outer shell, B an inner shell spaced from the outer to form an annular insulating-chamber C and insulating-spaces D and E at the ends. In this instance the inner shell is composed of a cylindrical section F, provided with depressed heads G and H, the heads being flanged, as at I, and the flanges united to the cylindrical body in any preferred manner, preferably by welding. The outer section referred to is composed of two stamped or drawn sections J and K, formed each with a head, as L, which in turn has formed in it an annular spacing-flange M, adapted to engage the ends of the inner section.

In assembling the parts the drawn sections are placed over the ends of the inner section until an engagement is effected between the inner-section ends and the annular flange. The drawn sections are united at their meeting edges by means of a seam O, formed from the adjoining portions of the sections. One of the sections is provided, preferably, with an angle-shaped flange P, Fig. 7, while the complementary section has formed therein a lateral annular flange Q. In forming the

seam the upwardly-projecting portion R of 55 the flange P is folded over into contact with the flange Q, and then both flanges are bent or pressed over into contact with the body of the outer section, as indicated in Fig. 9, a tight and waterproof seam being thus produced.

In Fig. 2 I have shown the outer section formed of a single cylindrical section constituting the body and heads set within the body, as previously described, and formed 65 each with an annual retaining and spacing flange, as R'. The inner section in this instance is composed of complementary drawn sections engaging the outer section and united to one another, as just described.

In Fig. 3 both the inner and outer shells are shown as composed of complementary drawn sections, each section being so curved or flared as to produce when assembled the bilge form of barrel.

In Fig. 4 the construction is similar to that of Fig. 3 in so far as the inner shell is concerned. The outer shell is formed of complementary drawn sections S and T, united by a third or intermediate section U, the connection between the sections being by means of the seam already described.

In Fig. 5 a type of insulated barrel is shown having a maximum amount of insulating-space. This is accomplished by forming the 85 inner shell of the drawn cylindrical section as indicated at V and W and the outer shell in bilge form, having preferably the intermediate uniting section Y.

From the forgoing description it will be observed that either or both of the shells may be composed of drawn sections and that said sections may be either united directly at their meeting edges or portions or by means of a third intermediate section, as described, the 95 latter being sometimes the preferable construction, as it requires stamp-sections of less depth, which is desirable for obvious reasons.

What I claim is—

1. A metallic barrel consisting of two 10 closed shells arranged one within the other, one being formed of oppositely-disposed drawn headed sections, and annular spacing-flanges upon the heads or ends of the complementary shell with which the drawn sections engage.

2. A metallic barrel comprising an outer inclosing casing composed of two drawn

headed sections formed each with a spacing-flange, and an inner closed shell engaging the flanges.

3. A metallic barrel consisting of an outer shell or casing composed of two drawn headed sections, the heads being oppositely disposed and formed each with an annular spacing-flange, and an inner closed shell engaging and held against relative movement by the head-flanges.

4. A metallic barrel comprising complementary inclosing casings arranged one

within the other, one being formed of oppositely-disposed drawn headed sections, and spacing-flanges upon the heads of one of the casings engaging the ends or heads of the complementary casing.

In testimony whereof I affix my signature in presence of two witnesses.

CHARLES L. COFFIN.
